UNITED STATES PATENT OFFICE.

HARRY SPENCER WHEATON, OF DALLAS, IOWA.

COMBINED CUT-OUT AND LIGHTNING-ARRESTER FOR TELEPHONE SYSTEMS.

1,212,300.

Specification of Letters Patent. Patented Jan. 16, 1917.

Application filed May 3, 1916. Serial No. 95,137.

To all whom it may concern:

Be it known that I, HARRY S. WHEATON, a citizen of the United States, residing at Dallas, in the county of Marion, State of Iowa, have invented a new and useful Combined Cut-Out and Lightning-Arrester for Telephone Systems; and I do hereby declare the following to be a full, clear, and exact description of the invention, such as will enable others skilled in the art to which it appertains to make and use the same.

This invention relates to an improved combined cut-out, and lightning arrester for telephone systems, and an object of the invention is to provide an improved device of this design having simple, efficient and practical features of construction.

Another object of the invention is the provision of a device of this character having means, whereby the telephone may be thrown out of circuit and the arrester remain in circuit.

It has been found that, during electrical storms and other electrical disturbances in the higher stratas of the atmosphere, it is very dangerous to use telephones, owing to the liability of receiving shocks.

Therefore it is another object of the invention, to provide an improved device for cutting out the telephone instrument from the line wires, so that the charge or electrical current from the atmosphere will be transmitted through a series of resistance members and transferred to the ground, thereby avoiding accidents occurring to the users of the telephone.

In practical fields the details of construction may necessitate alterations, falling within the scope of what is claimed.

40 The invention comprises further features and combination of parts, as hereinafter set forth, shown in the drawings and claimed.

In the drawings: Figure 1 is a view in side elevation of the improved combined cut-out and lightning arrester to telephones. Fig. 2 is a sectional view of the same. Fig. 3 is a sectional view on line 3—3 of Fig. 1. Fig. 4 is a sectional view on line 4—4 of Fig. 1. Fig. 5 is a view in elevation and partly in section of the improved controlling lever for cutting the device into and out of circuit. Fig. 6 is perspective views of parts of the plates 6 and 6^c, 7 and 7^a, and 8 and 8^a showing the wires. Fig. 7 is a diagrammatic view of the wiring for the combined cut-out and lightning arrester for telephone

systems, showing the parts of the arrester partially separated disassembled.

Referring more especially to the drawings, 1 designates a plate, which may be constructed of brass or any other suitable metal, and which is provided with a screw 2, whereby the plate may be fastened to any suitable stationary support, or upon the box frame of the telephone, or in close vicinity thereto.

Arranged adjacent the plate 1 is a body of hard rubber or insulating material 3. A plurality of elongated bolts 4 (which are provided with tubes or coatings or sleeves of insulating material or rubber 5) is provided, and which are passed through the plate 1 and the body or member of insulation 3, and also through the conducting plates 6 and 6^c, 7 and 7^a, and 8 and 8^a. The plates 6 and 6^c are connected by a transverse wire or lead 6^a, while the plate 6^c on the right is connected by a wire or lead 6^b to the lower right hand plate 7^a, from which a wire or lead 16^a extends designed to be grounded in any suitable manner. The main line wire 38^a is connected to the plate 7. A lead or wire 16 is connected to a terminal member 16^d (which is coöperated with by a part of the receiver hook). This wire or lead 16 is in turn connected at 17^c to the wire or lead 40. Thus, it will be seen that when the terminals 20 and 21 are in contact, the bell of the local phone may be rung by reason of being in circuit with the main line. The plates 8 and 8^a are provided with wires or leads 17^a and 17. Arranged between the plates 6 and 6^c, and 7 and 7^a, are blocks of carbon 10 and 10^a, and 11 and 11^a. The upper carbon blocks 10 and 10^a are held separated by strips or plates of mica 12 and 12^a.

Extending vertically with its upper part between the blocks of carbon 10 and 10^a, and its lower portion between the carbon blocks 11 and 11^a and between the adjacent edges of the plates or strips of mica 12 and 12^a is a conducting plate 13, the lower edge of which terminates a short interval below the under surface of the carbon blocks 11 and 11^a. The upper portion of the conductor plate 13 is made integral with a horizontal conductor plate 13^a, which spans from the plate 6 to the opposite plate 6^c, there being a space between the two plates 6 and 6^c to which a restricted part or tongue 13^b of the body of insulation 3 extends. As shown in the drawings, the adjacent edges of the plates 7 and 7^a, and 8 and 8^a respectively are

spaced apart. As will be clearly observed the upper plates 7 and 7^a and the plates 8 and 8^a are held separated by the fiber or insulating plates or members 15, through which and through the plates 7 and 7^a and 8 and 8^a the screws 4 extend, so as to hold the various parts together. The lower ends of the bolts 4 are provided with nuts 18, to hold the parts in position. Between the nuts 18 and the plates 8 and 8^a are insulating washers 18^a. The end portions 19 of the plates 7 and 7^a and 8 and 8^a are constructed to provide the contact terminals 20 and 21, which are yieldable. However, the contact terminals 21 are more yieldable than the terminals 20. The terminals 21 are curved as shown at 22 and 23, thereby forming crotches 24.

The plate 1 at one end is provided with a slot 25 and downwardly extending ears 26, which are disposed upon opposite sides of said slots. A lever 28 is pivoted upon a pin 29, which is mounted in bearings of the ears 26. The upper portion of the lever terminates in a handle 30, and extending laterally in opposite directions from the lower end of the lever 28 are sleeve bosses 33, in which a pin 34 is mounted, there being rollers 35 upon the opposite end of said pin. When the lever is moved in the direction of the arrow a, the rollers 35 (which are constructed of insulating material) cam against the terminal contacts 21, until the rollers engage the crotches 24, thereby throwing the contacts 21 in engagement with the terminal contacts 20, and holding them in contact, in which case the telephone is in service with the main line wire. However, in case of an electrical disturbance in the atmosphere, the lever may be moved in the opposite direction, disengaging the rollers from the crotches 24 and the terminal contact 21, whereby the terminal contacts 20 and 21 will automatically separate, thereby cutting out the telephone circuit from the service or main line. As shown in Fig. 7, there is a receiver 39 illustrated supported by the unusual receiver hook, and extending from the receiver 39 is a wire or lead 40, which connects at 49 to the telephone bell 51. The wire or lead 17^a of the plate 8 connects to the receiver hook, while the wire or lead 17 from the plate 8^a connects at 17^b to the telephone bell 51. The wire 16^a (which is connected to the plate 7^a) is connected to the ground at 53. Also connected to the receiver 39 is a wire 41, which in turn connects to the secondary coils 42, which in turn are connected to the ground, as shown at 45. A transmitter 50 is provided, which is connected to the primary coils 43 by means of the wire or lead 48. The primary coils 43 are in turn connected by the wire or lead 44 to the battery 46, which in turn is connected to the transmitter

50 by the wire or lead 47. As before stated, when the terminals 20 and 21 are separated, the telephone circuit is out of circuit with the service or main line 38^a, and it will be observed that any lightning discharges that 70 may be received or conducted on the main or service line, will be carried to the ground by virtue of the resistance means. For instance, in case of a lightning discharge being of a low frequency, it will jump from the carbon 75 resistance member 11 to the carbon resistance member 10, across the insulating mica 12, and in coming in contact with the conductor plate 6, will escape to the ground over the wires 6^a and 6^b, and the wire 16^a. Should 80 the frequency be high, the self-induction of the sharp turn between the wires 6^a and 6^b will more or less be the impedance of charge, and the resistance carbons 10^a and 11^a with the carbons 10 and 11 form the surfaces over which this arcing will take place. The plates 6 and 6^c are securely electrically joined by the wire or lead 6^a. This is done to guarantee a satisfactory contact between the upper portion 13^a of the T- 85 plate and the conductor plates 6 and 6^c, the assumption being that neither of the plates 6 and 6^c may not be more or less in good contact with the T-shaped plate. However, when the terminal contacts 20 and 21 are 90 again closed, by throwing the lever 28, the telephone circuit is again in circuit with the main or service line, hence it will be observed, the course of the circuit, when the receiver 39 is removed from its hook, by 95 tracing over the various wires, from the battery, to the secondary and primary coils, hence, to the receiver, and over the plate 7 and 7^a, and 8 and 8^a, to the ground, and to the telephone, not shown, at the other end 100 of the line. The current, in passing over the wire 40, from the receiver, divides at 17^c, a portion going over the wire 17^a, over the plates 8 and 7 over the main line 38^a to the other telephone at the other end of the line, 105 the other portion of the current passing to the bell 51 over the wires 17 to the plates 8^a and 7^a, to the ground over the wire 16^a, to the telephone, not shown, at the other end 110 of the line. It will be noted that the current, 115 when the telephone is in service, is prevented from entering the resistance members owing to the insulating mica strips 12 and 12^a, and owing to the current being steady and direct.

The invention having been set forth, what is claimed as new and useful is:

1. A combined cut-out and lightning arrester comprising a plate, an insulating body member adjacent thereto, plates adjacent the under part of the body, two sets of conducting plates, one set having connections with the main line and the ground, the other set having connection to the wires of a telephone receiver and bell, means for 120

insulating the plates of one set from the plates of the other set, a series of resistance members between the ground and the main line connected plates and the plates adjacent the insulating body, insulated means extending through the first plate, the body, the plates adjacent the under part of said body and the two sets of plates for holding the parts together, the two sets of plates having yieldable terminal contacts, and means for throwing the parts together, the two sets of plates having yieldable terminal contacts, and means for throwing said contacts in and out of engagement.

2. A combined cut-out and lightning arrester comprising a plate, an insulating body member adjacent thereto, plates adjacent the under part of the body, two sets of conducting plates, one set having connections with the main line and the ground, the other set having connections to the wires of a telephone receiver and bell, means for insulating the plates of one set from the plates of the other set, a series of resistance members between the ground and the main line con-

nected plates and the plates adjacent the insulating body, insulated means extending through the first plate, the body, the plates adjacent the under part of said body and the two sets of plates for holding the parts together, the two sets of plates having yieldable terminal contacts, and means for throwing said contacts in and out of engagement, said operating means comprising a lever having rollers at its lower end, the upper terminal contacts having crotch portions to receive said rollers, said resistance means comprising upper and lower sets of carbon members, and a plate between the upper carbon members and extending between the lower carbon members.

In testimony whereof I have signed my name to this specification in the presence of two subscribing witnesses.

HARRY SPENCER WHEATON.
